UNITED STATES PATENT OFFICE.

GEORGE E. PANCOAST, OF NEW YORK, N. Y.

PRINTING-PRESS.

1,028,485.

Specification of Letters Patent. Patented June 4, 1912.

Application filed December 30, 1905. Serial No. 293,928.

To all whom it may concern:

Be it known that I, GEORGE E. PANCOAST, a citizen of the United States, and a resident of New York city, borough of Brooklyn, county of Kings, and State of New York, have invented certain new and useful Improvements in Printing-Presses, of which the following is a specification.

My invention relates to printing presses; and while as to some of its features it may be applied to presses of various kinds, it is more particularly directed to rotary presses having a plurality of printing couples for printing on one or both sides of a web or a plurality of webs.

My invention has for an object to provide a construction whereby the parts or elements of a press may be arranged in various operative or physical relations, as may be required, to produce the desired size or character of product or to produce a press of a desired shape either with respect to the space available for its location or with respect to the accessibility of its parts or with respect to both considerations.

More particularly my invention has for an object to provide a set of press elements which may be duplicated and assembled in various operative or physical relations to produce presses of numerous forms or capacities and to enable the form to be adapted to the size or capacity.

These and other objects of the invention will in part be obvious and in part be more fully explained herein.

My invention consists in the novel parts, improvements, combinations, and arrangements herein shown and described.

In the accompanying drawings, which are referred to herein and form a part hereof, are illustrated several embodiments and modifications of the invention, the same serving in connection with the description herein to explain the principles thereof.

Of the drawings: Figure 1 is a side elevation illustrating certain press elements constructed in accordance with some of the features of my invention, some parts being diagrammatically indicated and others broken away to more clearly illustrate the construction. Fig. 2 is a diagram, illustrating an assemblage of the parts different from that shown in Fig. 1. Fig. 3 is a transverse section of one of the elements shown in Fig. 1. Fig. 4 is a plan view of

the same. Fig. 5 is a perspective view of a detail. Fig. 6 is a diagrammatic view, illustrating in side elevation one form of press which may be produced by assembling the parts shown in Figs. 1 to 5, inclusive. Figs. 60 7 and 8 are similar views, illustrating other forms of presses which may be produced by different assemblages of the same parts. Figs. 9 and 10 are similar views, illustrating two forms of presses that may be produced by a set of elements, one of which differs from the corresponding element of the set shown in Figs. 1 to 5, inclusive.

In accordance with the embodiment of the invention illustrated in Figs. 1 to 5, inclusive, two standard press elements are provided, the same being so constructed that duplicates of them may be assembled in various operative relations to produce presses of numerous forms and capacities. 70 The set of elements shown comprises a printing couple element A and an inking mechanism element B.

In accordance with one feature of the invention, the printing couple element A is 80 so constructed that duplicates of it may be assembled with the parts and particularly the printing couples in various operative relations as regards the distance between adjacent couples, either the linear distance between the corresponding members of the couples or the linear or angular distance between the planes of the couples. It is in accordance with a feature of the invention, also, that the printing couple element is 90 so constructed that the inking mechanism element may be assembled in various relations to the design member of the couple or in various positions with relation to said member, having reference to the plane of the 95 couple.

As shown, the printing couple element comprises impression and design cylinders 1 and 2, respectively, and a frame in which said cylinders are mounted in coöperative 100 relation. This frame may vary as to its shape and construction between wide limits. As shown, this frame comprises a pair of side members 4 and 5, the same being, preferably, and as shown, substantial duplicates 105 of each other as to shape and construction except that they may be rights and lefts. The side members 4 and 5 may be secured together in any suitable way. As shown, they are secured together by a transverse 110

girder 6 which is rigidly bolted at its opposite ends to the side frames. If desired, two of these girders may be employed, one on either side of the printing couple. Preferably, however, only one girder is employed, the opposite side of the frame being securely stayed when assembled in a press by being attached to an adjacent printing couple element or some other part of the press. In accordance with one feature of the invention, however, provision is made for the attachment of the securing means for the side frames in various positions. As shown, see Figs. 3 and 5, the frames of the element 15 are drilled and tapped on both sides of the couple so that the girder 6 may be secured in either of the two positions, as may be found convenient or desirable, when assembling the elements in a press.

20 In order that the printing couple element may be assembled in a press with the printing couple in various operative or physical relations to other parts of the press, the side frames 4 and 5 are provided with a plurality 25 of seats or surfaces by means of which the element may be assembled and secured in place in the press. In accordance with the preferred construction and as illustrated, the frames are provided with two surfaces 7 and 30 8 whereby the position of the element may be fixed with relation to other parts of the press, said surfaces preferably being located at a suitable angle with relation to each other and at the same distance from the axis 35 of the impression cylinder of the couple and at the impression cylinder end of the frame so that the element may be secured in place in different positions with respect to the angle which the plane passing through the axes 40 of the cylinders bears to the horizontal or to the corresponding planes of other couples. The particular angle which the surfaces 7 and 8 bear to each other, as shown in the drawings, has been found to be a convenient 45 angle.

The side frames, in accordance with another feature of the invention, are provided adjacent to the design cylinder with a plurality of surfaces by which the attachment 50 of the inking mechanism element in various operative relations to the design cylinder is facilitated. As shown, the frame is provided at this end with three surfaces 9, 10, and 11, the surfaces 9 and 10 preferably 55 bearing substantially the same angle to each other as the surfaces 7 and 8, while the surface 11 extends transversely to the plane which passes through the axes of the cylinders. These surfaces are preferably, and as 60 shown, located at the same distance from the axis of the design cylinder so that the inking mechanism will be in proper operative relation with the design cylinder in any one of the three positions. As a matter of 65 convenience and with the object in view of

making the side frames 4 and 5 as small as possible, a pair of brackets 12 and 13 is provided to give the surface 11 ample extent to enable the inking mechanism to be firmly secured in place, said brackets, when used, 70 being secured upon the surfaces 9 and 10, as indicated. The brackets 12 and 13 are also used to supplement the surfaces 9 and 10 when the inking mechanism is secured to one of said surfaces, the bracket 13 being 75 used in connection with the surface 9, as indicated in the Fig. 2, and the bracket 12 being used in connection with the surface 10 when the inking mechanism is secured to the latter surface, the bracket 12 or 13 in each 80 case being secured upon the surface 11.

The cylinders of the printing couple may be secured in place in the frame in any suitable way. Preferably, however, provision is made to permit the cylinders to be removed from the frame without removing the frame from a press in which it may be assembled. To this end, the side frames 4 and 5 in the embodiment of the invention illustrated in Figs. 1 to 5, inclusive, are provided with slots 14, 15 so that the cylinders together with their bearings can be removed and replaced in the frame. The box bearings 16 of the cylinder 2 may be rigidly held in the slots 15 in any suitable way, as by 90 filling pieces or brackets 17, which, as shown, are bolted in the slots 15 and form parts of the supporting surfaces 11 for the inking mechanism.

The bearing boxes 18 for the cylinder 1 are 100 adjustably mounted so that the pressure between the cylinders may be regulated, and preferably means are provided also for effecting a relative movement between the cylinders so that they may readily and at 105 will be brought into and out of co-operative relation. As shown, the boxes 18 are movably mounted in the slots 14 and their movements are affected and controlled by eccentrics 19 mounted in pieces 20 and connected 110 with the bearings 18 by means of links 21 and intermediate pieces 22. For the purpose of regulating the pressure between the cylinders the pieces 20 are adjustably secured in position by means of cap pieces 23 which are removably secured across the open 115 ends of the slots 14 and are adjustably connected with the piece 20 by means of the set screws 24 and retaining bolt 25. The eccentrics 19 may be operated in any suitable 120 way. As shown, they are provided with arms 26 which are connected by links 27 to cranks 28 fixed at the opposite ends of a shaft 29 which extends transversely through the printing couple frame and thus forms a common operating mechanism for the eccentrics at the opposite ends of the impression cylinder 1. The shaft 29 may be driven in any suitable way. Preferably, and as shown, it is provided at each end with a 130

gear 30 which is adapted to mesh with a pinion 31. The pinions 31 are loosely journaled on the side frames 4 and 5 and have provision for engagement by a suitable wrench. To facilitate the attachment of the printing couple element in various positions with relation to other elements or parts of the press, the printing couple frame is preferably so constructed that the operating shaft 29 may be mounted on either side of the printing couple and so that the driving pinion 31 may be located on either side of the shaft 29 in either position. To this end, the frames 4 and 5 are provided with suitable bearings 29^a for the shaft 29 on both sides of the printing couple and also with bearings 31^a for the pinions 31 on both sides of each of the bearings 29^a, all as clearly shown in Figs. 1, 3, and 5.

The inking mechanism may be of any suitable construction and it may be provided with any suitable form of frame which is adapted to be secured in the various positions provided for its reception on the frame of the printing couple. As shown, the inking mechanism comprises a fountain 32, a fountain roller 33, ductor 34, distributing cylinders 35 and 36, soft distributing and conveying rollers 37, metallic riders 38, and form rollers 39. The parts 32 to 37, inclusive, as shown, are mounted in the frame comprising side members 40 having at their bases suitable lugs or flanges 41 by which they may be secured to any one of the surfaces 9, 10, and 11 of the printing couple element. In accordance with the construction shown, the riders 38 and form rollers 39 on each side of the inking mechanism are mounted in auxiliary frames 42 which are pivotally mounted on the side frames of the printing couple elements and are provided with suitable connections 43 whereby they may be moved so as to carry the form rollers into and out of operative relation with the design cylinder. In order that the frames 42 may be secured in the several positions corresponding to the several positions of the ink frames 40, the side members 4 and 5 are provided with a series of suitably spaced openings 42^a adapted to receive the pivots of the frames 42, as shown in Figs. 1, 2, and 5.

The inking mechanism may be driven in any suitable way. In the particular embodiment of the invention illustrated the inking mechanism is driven from a gear 44 on the shaft of the design cylinder 2 by a gear 45 which meshes with pinions 46 on the shafts of the rollers 36, the other parts of the inking mechanism being suitably geared with one or the other of the rollers. In order that the driving connections for the inking mechanism may not be disarranged or require adjustment for the various positions of the inking mechanism with relation to

the design cylinder, the surfaces 9, 10, and 11 are preferably arranged equidistant from the axis of said cylinder, as shown.

The printing couple together with its inking mechanism may be driven in any suitable way, as by a bevel gear 47 fixed on the shaft of the cylinder 2, the two cylinders of the couple being geared to rotate in unison by means of gears 48, the latter preferably being split as indicated in Fig. 4, and the parts made adjustable with relation to each other to take up backlash.

It will be observed that duplicates of the elements shown in Figs. 1 to 5 may be assembled in various relations to produce presses having different forms and capacities, suitable frame mechanism being provided to support the assembled elements in the desired relations.

In Fig. 6 is diagrammatically illustrated a convenient manner of assembling the elements to form a web perfecting press. In this construction the printing couple elements A¹ and A² are employed, the same being secured together with the surface 7 of one in contact with the surface 8 of the other so as to bring their impression cylinders into a close relationship and to separate the design cylinders to afford ready access to the same. The inking mechanism elements B¹ and B² are secured to the elements A¹ and A², respectively, at the surfaces 11.

To support the assembled elements properly a base 50 is provided, the printing couple elements being supported from the base by a pair of frame members, one of which is indicated at 51 and the outer ends of the inking mechanisms preferably being supported and steadied by a pair of frame elements, one of which is indicated at 52. The elements A may be more firmly united by means of brackets 53 and 54. The printing couples may be driven in unison by any suitable means. As shown, a vertical driving shaft 55, receiving power from any suitable source, is directly geared by suitable bevel gears with the shafts of the design cylinders.

The press illustrated in Fig. 7 includes three sets of elements arranged to print two colors on one side of a web and one on the other. Two of the printing couple elements A¹ and A² are arranged one above the other with the surface 8 of one facing the surface 7 of the other so that the planes of the printing couples are at an angle to each other as in the form of press shown in Fig. 6; but in this case the two elements are separated by a web forwarding anti-offset mechanism 56, which with its frame may form a third standard element C of press construction. The third printing couple element A³ is secured to the second element A² with the surface 7 of the two couples in

contact so that these two printing couples will bear a different relation to each other from that which the couples of elements A^1 and A^2 bear to each other, this arrangement being a convenient one for the type of press shown both as regards the lead of the web and as regards the accessibility of the parts. In this construction each of the inking mechanism elements B^1 , B^2 , and B^3 is secured to the surface 11 of the corresponding printing couple element. The frame construction of this press comprises a base 57, standards 58 and 59 for supporting the outer ends of the inking mechanism elements B^2 and B^3 , frame sections 60 and 61 for supporting the printing couple elements from the base, and suitable braces 62, 63, and 64. The driving mechanism shown comprises a vertical shaft 65 which receives power from any suitable source and is geared by miter gears to the design cylinders of the elements A^1 and A^2 . The printing couple of the element A^3 is driven from that of A^2 by means of a transverse shaft 66 which is connected by bevel gears to the design cylinders of the two couples.

The press shown in Fig. 8 is adapted to print four colors on one side of the web and one on the reverse side. Of the five printing couple elements employed, the first four A^1 , A^2 , A^3 , and A^4 are assembled with the surface 7 of one facing the surface 8 of the other, these couples, as shown, being separated from each other by a series of web transferring elements C^1 , C^2 , and C^3 . By reason of this arrangement the impression cylinders of the couples are located substantially in the arc of a circle and in such relation to each other that they may be easily reached from the central space which is provided by the arcuate form of the press. At the same time the design cylinders are suitably separated and readily accessible. The element A^5 is located below the element A^4 with the surfaces 7 of the two elements facing each other but separated by a frame element 67 corresponding to one of the web transferring elements C .

The inking mechanism elements may be variously arranged. As shown, the inking mechanism elements B^1 and B^2 are secured to the surfaces 11 of the corresponding printing couple elements A^1 and A^2 ; and the inking mechanism elements B^3 , B^4 , and B^5 are secured to the surfaces 9 of the printing couple elements A^3 , A^4 , and A^5 , respectively. The inking mechanism element B^3 is shown as forming a support for the printing couple element A^5 and the parts superimposed thereon. The frame of this press comprises a base 68 and frame members 69, 70, and 71. The printing couples may be driven in any suitable way. As shown, the impression cylinder of the first couple is driven by means of a train of gears 72 from

a suitable power shaft 73, and the other couples are driven from the first couple by means of a master gear 74 which is suitably mounted in concentric relation with the several impression cylinders of the first four printing couples. The last couple of the series is driven from the gear 74 by a pair of intermediate gears 75 which mesh with the gear on the design cylinder of the couple.

In Fig. 9 a somewhat different form of printing couple element D is illustrated. In accordance with the construction shown, each of the side frames of the element is provided with four surfaces 76, 77, 78, and 79, adapted to be used in securing the couples to each other or to other parts of the press in various operative relations and to surfaces 80 and 81 by means of which the inking frame elements E may be secured in two different operative relations to the design cylinders of the couples. In the arrangement shown the two upper printing couple elements D and D^1 are assembled with the frame surfaces 78 and 77, respectively, in contact; the elements D^1 and D^2 with the surfaces 79 and 76, respectively, in contact; the elements D^2 and D^3 with the surfaces 78 and 77, respectively, in contact; the elements D^3 and D^4 with the surfaces 79 and 76, respectively, in contact; and the elements D^4 and D^5 with the surfaces 78 and 77, respectively, in contact. The inking mechanism elements E, E^1 , and E^2 are secured to the surfaces 80 of the printing couple elements D, D^1 , and D^2 , respectively, while the inking frame elements E^3 , E^4 , and E^5 are secured to the surfaces 81 of the printing couple elements D^2 , D^4 , and D^5 , respectively. As shown, a supporting frame 82 is provided for the two lower printing couple elements D^4 and D^5 , and braces 83 are provided between the elements D^2 and D^5 and D and D^3 , respectively. One or more webs may be fed to this machine and receive one or more impressions on either or both sides. As shown, the printing couples of the respective pairs of elements D, D^1 , and D^2 , D^3 , and D^4 , D^5 , act each to print and perfect a single web, the web supply rollers 84, 85, and 86 being suitably supported upon a standard 87. The printing couples may be driven in any suitable way, as by the vertical driving shafts 88 and 89 which are respectively geared to the impression cylinders of the couples D, D^2 , D^4 , and D^1 , D^2 , and D^5 .

In Fig. 10 is illustrated a press for printing four colors on one side of a web, the same being formed by a suitable arrangement of the printing couple elements D and the inking mechanism elements E. In this press the printing couple elements D^1 , D^2 , D^3 , and D^4 are arranged in the form of a cross, the adjacent ends of the elements being separated by a series of web forwarding

elements C¹, C², and C³. The inking mechanism elements E² and E³ are secured to the uppermost surfaces 80 of the elements D² and D³ and the inking mechanism elements E¹ and E⁴ are secured to the lowermost surfaces 81 of the elements D¹ and D⁴, respectively, said inking frame elements in this instance forming the main support for the other parts of the press. This press may be driven in any suitable way, as by a master gear 90 from which the impression cylinders of the printing couples are directly driven, said gear 90 receiving power from any suitable source, as from a vertical shaft 91 and suitable gear connections.

Other forms of printing press elements and other arrangements of the forms of elements shown will readily suggest themselves to those skilled in the art, the principles and advantages of the invention once being understood. My invention therefore, in its broader aspects, is not limited to the particular construction shown nor to any particular construction by which the invention has been or may be carried into effect.

What I claim is:

1. A rotary printing press including in combination, a plurality of printing couples, and a plurality of frames, one for each couple, said frames being so constructed that by means thereof the couples may be assembled with the adjacent couples at various distances from each other.

2. A rotary printing press including in combination, a plurality of printing couples, and a plurality of frames, one for each couple, said frames being interchangeable and so constructed that by means thereof the couples may be assembled with the adjacent couples at various distances from each other.

3. A rotary printing press including in combination, a plurality of printing couples, a plurality of inking mechanisms, one for each couple, and a plurality of frames in which the couples are mounted, said printing couples, inking mechanisms and frames being respectively interchangeable, and said frames being so constructed that the inking mechanisms and the design cylinders of the respective couples may be assembled in various relations to each other.

4. A printing press including in combination, a design cylinder, an inking mechanism, and a frame in which said design cylinder is mounted, said frame being so constructed that the inking mechanism may be assembled in various relations to said design cylinder.

5. A printing press including in combination, a plurality of design cylinders, an inking mechanism for each design cylinder, and a frame for each design cylinder, said frames being so constructed that the respective design cylinders and inking mechanisms may be assembled in various relations to each other.

6. A rotary printing press including in combination, a rotary printing couple, and a frame for said couple, said frame having provision for the assembling of an inking mechanism in a plurality of positions with relation to the design member of the printing couple. 70

7. A rotary printing press including in combination, a rotary printing couple, and a frame for said couple, said frame by reason of its shape having provision for the assembling of the printing couple at a plurality of distances from adjacent parts of the press. 75

8. A rotary printing press including in combination, a rotary printing couple, and a frame for said couple, said frame having provision at one end for the attachment of an inking mechanism in a plurality of positions with relation to the design member 80 85

9. A rotary printing press including in combination, a rotary printing couple, and a frame for said couple, said frame having provision at one end for the assembling of 90 an inking mechanism in a plurality of positions with relation to the design member of the printing couple and at the other end for the assembling of the printing couple to other parts of the press in a plurality of 95 positions with relation thereto.

10. A printing press including in combination, a plurality of printing couples, an inking mechanism for each couple, and a frame for each couple, each frame having 100 provision at one end for the assembling of the corresponding inking mechanism in a plurality of positions with relation to the design member of the couple.

11. A printing press including in combination, a plurality of printing couples, and a frame for each couple, each frame by reason of its shape having provision at one end for the assembling of the printing couples in a plurality of relative positions. 105

12. A printing press including in combination, a plurality of printing couples, an inking mechanism for each couple, and a frame for each couple, each frame having provision at one end for the assembling of the corresponding inking mechanism in a plurality of positions with relation to the design member of the couple and at the other end for the assembling of the printing couples in a plurality of relative positions. 115

13. A set of printing press elements comprising a printing couple element, and an inking mechanism element, said printing couple element being so constructed that the inking mechanism element may be assembled in various operative relation to the design member of the couple. 125

14. A set of printing press elements comprising a printing couple element, and an inking mechanism element, said printing 130

couple element being so constructed that duplicates thereof may be assembled in various operative relations and that the inking mechanism element may be assembled 5 in various operative relations to the design member of the couple.

15. A printing press element comprising a printing couple, and a frame for the couple so constructed that by means thereof 10 duplicate elements may be assembled with the couples at various distances from each other.

16. A printing press element comprising a printing couple, a frame in which the 15 couple is mounted, and means for effecting a relative movement between the members of the couple, said frame having provision for assembling part of said means in various operative relations to the couple.

20. 17. A printing press element comprising a printing couple, a frame in which said couple is mounted, and means for moving one member of the couple with relation to the other including operating devices, said 25 frame having provision for assembling said operating devices in various operative relations to said couple.

18. A printing press element comprising a printing couple, a frame in which said couple is mounted, said frame including 30

side members and means for securing said side members together, said side members having provision for the attachment of said securing means in various positions.

19. A printing press element comprising 35 a printing couple, a frame in which said couple is mounted, said frame including side members so constructed that duplicates of the element may be assembled in various operative relations, and means for securing 40 said side members together, said side members having provision for the attachment of said securing means in various positions.

20. A printing press element comprising 45 a printing couple, a frame for the couple so constructed at one end that by means thereof duplicate elements may be assembled in various relations to each other.

21. A printing press element comprising 50 a printing couple, and a frame so constructed at each end that by means thereof duplicate elements may be assembled with the couples in various operative relations.

In testimony whereof, I have signed my name to this specification, in the presence of 55 two subscribing witnesses.

GEORGE E. PANCOAST.
